(57) **CLAIM**

The ornamental design for a novel temperature monitor for freezers and coolers, as shown and described.

DESCRIPTION

FIG. 1 is an upper front right perspective view of a design of the novel temperature monitor.

FIG. 2 is an upper front left perspective view of the design of FIG. 1.

FIG. 3 is a lower front right perspective view of the design of FIG. 1.

FIG. 4 is a lower front left perspective view of the design of FIG. 1.

FIG. 5 is a right side view of the design of FIG. 1.

FIG. 6 is a left side view of the design of FIG. 1.

FIG. 7 is a front view of the design of FIG. 1.

FIG. 8 is rear view of the design of FIG. 1.

FIG. 9 is a top view of the design of FIG. 1; and,

FIG. 10 is a bottom view of the design of FIG. 1.

The broken lines showing environmental feature in FIGS. 1–10 are for illustrative purposes and form no part of the claimed design.
